DISPLAY BOX

Simon Quartin, Brooklyn, N. Y.

Application May 24, 1940, Serial No. 336,953

4 Claims. (Cl. 206—44)

This invention relates generally to containers and more particularly to display boxes.

Among the objects of the present invention is the provision of a display box which when the cover or top of the box is opened or raised, causes the bottom of the box to be elevated at the rear portions thereof so that the box bottom will be disposed at an angle with relation to the horizontal and will show the contents of the box in a pleasing and otherwise desirable manner.

Another object herein lies in the provision of a display box having the aforementioned qualities, yet which is of extremely simple construction, having a minimum of moving parts so that the same is fool-proof in operation.

Another object herein lies in the provision of a display box having the aforementioned qualities, yet which is of extremely simple construction, having a minimum of moving parts so that the same is fool-proof in operation.

Another object herein lies in the provision of novel display box constructions in which practically no additional material or labor is required so that the present display boxes may be manufactured with relatively no increase in cost over the cost of similarly constructed boxes which do not have applicant's display feature.

Another object herein lies in the provision of novel box construction, which may find use in a relatively large number of different styles of boxes with equal usefulness.

These objects and other incidental ends and advantages will more fully appear in the progress of this disclosure and be pointed out in the appended claims.

In the drawings, forming a material part hereof, similar reference characters designate corresponding parts throughout the several views.

Figure 1 is a view in perspective showing a first embodiment of the invention with the cover in a closed position.

Figure 2 is a view taken similarly to Figure 1 and shows the cover in an open position and the box bottom in an elevated position.

Figure 3 is a bottom plan view of Figure 1.

Figure 4 is a central, vertical, sectional view of Figure 3 as seen from the plane 4—4 and enlarged for purposes of clarity.

Figure 5 is a view taken similarly to Figure 4 but shows the position which the parts take when the cover is open and the box bottom is elevated.

Figure 6 is a bottom plan view of a second embodiment of the invention.

Figure 7 is a central, vertical, sectional view as seen from the plane 7—7 on Figure 6.

Figure 8 is a view similar to Figure 7, but

shows the position of the parts when the cover is opened and the box bottom is elevated.

Figure 9 is a central, vertical, sectional view of a third embodiment of the invention.

5 Figure 10 is a view taken similarly to Figure 9, but shows the cover in an open position and the box bottom in an elevated position.

Turning now to the embodiment of the invention illustrated in Figures 1 to 5, inclusive, the 10 display box generally indicated by numeral 10 includes a closure element 11 and a bottom element 12. While the present invention may be applied to boxes having a considerable number of different variations in external configuration, the box shown in Figures 1 to 5, inclusive, has generally a horseshoe shape and is illustrative of the use of the invention in connection with the box having an irregular shape.

The closure element includes a top wall 13, 20 front wall 14 and a curvilinear side wall 15, including generally the lateral portions 16 and 17, and the rear portion 18. The walls 13 to 18, inclusive, may be made of any suitable planar material such as sheet cardboard.

25 This material which forms the said vertical wall portions may be a long strip, the ends of which being joined in an inconspicuous location as for example at the corner 19. The vertical wall portions 14 to 18 inclusive thus form the rim 29 of the closure element 11, and the upper edge of said rim may be secured to the lower peripheral surface of the top wall 13 in any suitable manner.

30 The closure element covering means indicated generally by numeral 29 serves as a decorative covering for the closure element and also to reinforce the attachment of the upper edge of the rim 29 of the closure element to the under surface of the top wall 13. The closure element covering means includes the vertical portions 21 and the top horizontal portion 22.

35 The covering means 20 may be composed of paper, cloth or any desired decorative sheet material having the requisite tensile strength. 40 Figure 2 is a view taken similarly to Figure 1 and shows the cover in an open position and the box bottom in an elevated position.

Figure 3 is a bottom plan view of Figure 1. 45 The bottom element 12 includes the bottom wall 23 and the front wall 24, and a curvilinear side wall 25, which includes the lateral portions 26 and 27 and the rear portion 28. The walls 24 to 28 inclusive form the rim 31 and may be

50 made of any suitable planar material such as sheet cardboard. The material which forms the said vertical wall portions of the bottom element 12 may be a long strip, the ends of which are joined at an inconspicuous location as for example at the corner 19. The bottom element covering means generally indicated by numeral 30

55 is suitably secured to the inner vertical surfaces of the rim 31. The covering means 30 extends over the upper edge of said rim 31 and is also secured to the outer vertical surfaces of the rim.

Disposed directly below the bottom wall 23 is a bottom plate 32. The plate 32 follows the general configuration of the bottom wall 23, and is substantially equal in area to the area of the top wall 13, but has in addition a flange 33 which extends outwardly of the rim 29. The flange 33 is disposed at the edge of the plate 32, at that portion which is located forwardly of the bending line 34. The bottom plate 32 is preferably scored at the bending line 34 so that the bending or folding of the bottom plate about the bending line 34 is facilitated. The bending line 34 thus divides the bottom plate 32 into two portions, which with relation to the bottom wall 23 may be termed the stationary or forward portion 35 and the movable or rear portion 36. The forward portion 35 is positively secured to the under surface of the bottom wall 23 in any suitable manner, as for example by gluing. The connection of the bottom plate portion 35 to the bottom wall 23 is further accomplished by means of the bottom element covering means 30 which extends outwardly over the upper surface of the flange 33 and then extends inwardly for a suitable distance on the under surface of the flange 33 and portion 35.

The rear portion 36 of the bottom plate 35 is positively secured to the lower edge of the rear portion 18 of the rim 29 in any suitable manner, as by means of adhesive, and this attachment is reenforced by extending the closure element covering means 20 down and along the under surface of the rear portion 36. The lowermost inwardly extending edges of the closure element covering means 20 and the bottom element covering means 30 are further maintained in place by means of the bottom plate covering means 37, which is preferably adhesively secured to said edges and to the under surface of the bottom plate 32. While the bottom plate will function satisfactorily by simply compressing or scoring the same along the bending line 34, a more durable construction will result by reenforcing said bending line portion with a hinge 38. The hinge 38 may be paper or a thin strip of muslin or where the present construction is embodied in heavier or larger containers, may be of any other suitable construction.

As shown in Figure 2, the bottom element 12 may be provided with any auxiliary display means such as the shelf or panel 40 upon which may be suitably secured the article which it is intended the container shall act as a casing for, as for example, the bottle of perfume indicated by numeral 41. The panel 40 and the article 41 are omitted from the other views of the first embodiment for the purpose of clarity in the drawings.

The operation of the first embodiment is substantially as follows: When the container, display box 10, is in a closed position, it will appear as seen in Figure 1 with the flange 33 acting as a stop to prevent the parts, that is to say the closure element 11 and the bottom element 13, from telescoping too far, since in accordance with the present construction the upper edge of the rim 31 must be placed a suitable distance from the under surface of the top wall 13, as will be more fully described hereinbelow. The contact of the rear portion 36 of the bottom wall 23 also serves as a stop to prevent the parts from telescoping too far. With the container 10 resting upon any suitable flat surface, when the closure element 11 is manually grasped and raised it will swing upwardly and the front wall 14 will travel through an arcuate path. The closure ele-

ment 11 will pivot about the point 42, that is to say the lower rear edge of the rim 29, seen on Figure 4 and will move the bottom element 12 rearwardly, or to the right as seen in Figures 4 and 5. During this rearward movement of the bottom element 12, the forward edge of the flange 33 acts as a skid and will slide over the surface upon which the display box is resting. The elevation through an arcuate path of travel of the movable or rear portion 36 will result in raising the rear portion 36 of the bottom element 12. In its fully open position, the closure element 11 will rest upon the portion 18 and will appear as seen in Figures 2 and 5. In closing the closure element 11, the same is lowered and the movement of the parts just described will take place in reverse order. As may be seen in Figure 4, the upper rear edge of the rim 31 will follow a path of travel indicated by the dot dash line 20, 43 when the closure element 11 is raised or lowered.

In varying the size and shape of the closure element and bottom element for the purpose of utilizing the present construction for other sized display boxes, allowance must be made so that the distance from the bending line 34 to the point 44, that is the upper rear edge of the rim 31, must not be greater than the nearest distance from the line 34 to the under surface of the top wall 13. It is also desirable that a certain amount of clearance exist between the point 45, that is the upper edge of the front wall 24, and the inner surface of the front wall 14, so that these parts may pass each other as the closure element is raised. Where the display box is made of relatively flexible material however, as for example the lighter weights of cardboard, this clearance last described need not be given consideration as the parts will flex sufficiently to allow them to pass each other in opening and closing the display box.

Turning now to the second embodiment of the invention illustrated in Figures 6 to 8, inclusive, the display box generally indicated by numeral 45 10' includes a closure element 11' and a bottom element 12'. Although the construction of the second embodiment may be applied to boxes having a considerable number of different variations in external configuration, for purposes of illustration, the second embodiment is a rectangular box.

The closure element 11' includes a top wall 13', a front wall 14', side walls 16' and 17' and rear wall 18'. The walls 13' to 18', inclusive, may if desired be composed of a single sheet of planar material, such as sheet cardboard, the vertical wall portions 14' to 18', inclusive, thus forming the rim 29' of the closure element 11'. Where desired of course, the vertical wall portions may be composed of a single long strip of material, the ends of which are joined and the upper edges of which are adequately secured to the peripheral edges of the top wall 13'. It will be understood of course that where desired the closure member may be suitably covered with any decorative material.

The bottom element 12' includes the bottom wall 23', front wall 24', side walls 26' and 27' and the rear wall 28'. The vertical walls 24' to 28', inclusive, form the rim 31'. The bottom element 12' may be formed from a single sheet of planar material, or the rim may be a separate unit suitably attached to the upper surface of the bottom wall 23' at the peripheral edges thereof. The bottom element 12' may also, of course,

be suitably decorated with any desirable covering means. The bottom element 12' is pivotally connected to the closure element 11' by means of the hinge structure generally indicated by numeral 34'.

The hinge structure 34' includes a piece of tape or string 50' which is secured to the under surface of the bottom wall 23' by any suitable means as for example portions of gummed paper tape 51' and 52'. The outer ends of the string 50' are secured to the side walls 16' and 17' by similar pieces of gummed paper tape 53' and 54'. Since the portion of the string 50' existing between the inner ends of the paper tape portions 51' and 52' indicated by numeral 55' on Figure 6 performs no important function, the same may be omitted where desired and two separate pieces of string 50' may be utilized, one connecting the paper tape portion 51' with the paper tape portion 53', and another connecting the paper tape portion 52' with the paper tape portion 54'. The string 50' thus divides the bottom wall 23' into two portions, a forward portion 35' and a rear portion 36'. The bottom element 12' may be provided with any auxiliary display means similar to the panel 40 previously described.

The inner surface of the front wall 14' is provided with a stop 33' which may take the form of a small block of cardboard or wood adhesively secured to the inner surface of said wall.

The operation of the second embodiment is substantially as follows: When the display box 10' is in a closed position, it will appear as seen in Figures 6 and 7. The stop 33' acts to prevent the parts, that is to say the closure element 11' and the bottom element 12', from telescoping too much, since in accordance with the present construction, the upper edge of the rim 31' must be placed inwardly a suitable distance from the under surface of the top wall 13'. The contact of the rear wall 28' also serves as a stop to prevent the parts from telescoping too much. With the display box 10' resting upon any suitable flat surface, when the closure element 11' is manually grasped and raised, it will swing upwardly and the front wall 14' will travel through an arcuate path. The closure element 11' will pivot about the point 42', that is to say the lower rear edge of the rim 29', and will move the bottom element 12' rearwardly, or right as seen in Figures 7 and 8. During this rearward movement of the bottom element 12', the forward edge thereof acts as a skid and will slide over the surface upon which the display box is resting. The elevation through an arcuate path of travel of the rear portion 36' will raise the same. In this fully open position, the closure element 11' will rest upon the rear wall 18' and will appear as seen in Figure 8. In closing the closure element 11' the same is lowered and the moving of the parts just described will take place in reverse order. As may be seen in Figure 7, the upper rear edge of the rim 31' will follow a path of travel indicated by dash double dot line 43' when the closure element 11' is raised or lowered.

In varying the size and shape of the closure element 11' and bottom element 12' for changing the general capacity of the display box, allowance must be made so that the distance from the hinge structure 34' to the point 44', that is the upper rear edge of the rim 31', must not be greater than the nearest distance from the hinge structure 34' to the under surface of the top wall 13'. It is also desirable that adequate clearance exist between the point 45', that is the upper edge of

the front wall 24', and the inner surface of the front wall 14' so that these parts may pass each other as the closure element is raised. This action is illustrated in Figure 7 wherein the dot dash line shows the bottom element 12' in a partially rotated position.

Turning now to the third embodiment illustrated in Figures 9 and 10, inclusive, the display box generally indicated by numeral 10'' includes 10 a closure element 11'' and a bottom element 12''. This construction too may also be varied in size and shape, but for example is illustrated in a rectangular display box.

The closure element 11'' includes a top wall 15 13'', a front wall 14'', side walls 16'' and a rear wall 18''. The lower edge of the rear wall 18'' is provided with an inward extension 17'', the outer lateral ends of which join the lower edges of the side walls 16'' at the lower edges of said 20 side walls. The walls 13'', 14'', 16'' and 18'' and the extension 17'' may if desired be composed of a single sheet of planar material. The walls 14'', 16'' and 18'' form the rim 29'' of the closure element 11''. As herein previously described the rim may be composed of a single long strip of material, the ends of which are joined and the peripheral edges of which are secured to the peripheral edges of the top wall 13''.

The bottom element 12'' includes the bottom 30 wall 23'', the front wall 24'', side walls 26'' and the rear wall 28''. The vertical walls 24'', 26'' and 28'' form the rim 31''. The bottom element 12'' may be formed from a single sheet of planar material, or the rim may be a separate 35 unit suitably attached thereto. Both the closure element 11'' and the bottom element 12'' may be suitably decorated in any desirable manner as for example by painting or printing upon the same or by covering said elements with sheet 40 decorative material.

The bottom element 12'' is pivotally connected to the closure element 11'' by means of hinge 45 structure generally indicated by numeral 34''. The hinge structure 34'' comprises pins or hollow rivets 50'' which are oppositely disposed in the opposite side walls 16'' and 26'' of the closure element 11'' and the bottom element 12'' respectively. The rivets 50'' are coaxially aligned. Since the rivets 50'' do not extend any considerable 50 distance inwardly of the side walls 26'', they do not in any way interfere with the space within the bottom element within which goods may be placed for transportation or display. The bottom element 12'' may be provided with any 55 auxiliary display means similar to the panel 40 previously described.

The inner surface of the front wall 14'' is provided with a stop 33'' which may take any suitable form such as a block of cardboard or wood 60 adhesively secured to the inner surface of said wall or a small block of any suitable material riveted or stapled to said wall.

The operation of the third embodiment is similar to the operation of the prior described embodiments but differs principally therefrom in the fact that pivotal action takes place between the closure element and the bottom element about the pivotal points which are disposed (as viewed in Figure 9) above the bottom of the display 70 box 10''. This may be contrasted with the first and second embodiment in which pivoting occurs about a point substantially at the same level as the bottom of the elements 12 and 12'. With the rivets 50'' being located at an upper position 75 on the side walls of the closure and bottom ele-

ments, the bottom element will have a different path of travel. This path of travel may be seen in Figures 9 and 10 in which Figure 9 shows the bottom element at the start of its movement, and Figure 10 shows the bottom element with the display box 10" in its open position. Here again adequate clearance must be allowed between the point 44" and the under surface of the top wall 13" and in addition adequate clearance must be provided between the point 60" and the inner surface of the rear wall 18", and also the inner edge of the extension 17".

It may thus be seen that I have disclosed novel display boxes which are highly useful and permit of extremely economical production so that the same may be produced at a cost the same or only slightly greater than production not having my display feature. On the box construction shown, practically all of the operations in the construction thereof may be performed on known box-making machines so that an expensive outlay for new equipment for the production of these boxes is not necessary. In the first embodiment for example, which is based upon a covered box construction, that is, in which a skeleton box is used as a frame and decorative covering material is placed thereupon, the covering material in the closure element instead of being secured to the inner surface of the vertical walls completely around the edge thereof is merely allowed to extend in the rear and is secured to the under surface of the bottom plate 35. In a box having a normally flanged bottom element, it is only necessary to score the bottom plate and to secure the rear portion of said plate to the lower edge of the rear portion of the rim of the closure element in order to secure the elevating display feature in the bottom element. This means that such a box may be constructed and will require no more material than the construction of a similar box which is covered and has a bottom flange but which does not have my elevating display feature.

I wish it to be understood that I do not desire to be limited to the exact details of construction shown and described, for obvious modifications will occur to a person skilled in the art.

I claim:

1. A display box comprising: a closure element having a top wall and a first rim depending from said top wall, said first rim including a first front wall with a lower edge, opposed first lateral portions, and a first rear rim portion; a bottom element having a bottom wall and a second rim upstanding from said bottom wall, said second rim including a second front wall with an upper edge, opposed second lateral portions, and a second rear portion; and a bottom plate of substantially the same general configuration as said bottom wall, said bottom plate having a transverse bend dividing the bottom plate into a forward bottom plate portion and a rear bottom plate portion; said forward bottom plate portion being secured to the undersurface of said bottom wall; said rear bottom plate portion being connected to the lower edges of the first rear rim portion and the opposed first lateral portions.

2. A display box comprising: a closure element having a top wall and a first rim depending from said top wall, said first rim including a first front wall with a lower edge, opposed first lateral portions, and a first rear rim portion; a bottom element having a bottom wall and a second rim upstanding from said bottom wall, said second rim

including a second front wall with an upper edge, opposed second lateral portions, and a second rear portion; a bottom plate of substantially the same general configuration as said bottom wall, said bottom plate having a transverse bend dividing the bottom plate into a forward bottom plate portion and a rear bottom plate portion; said forward bottom plate portion being secured to the undersurface of said bottom wall; said rear bottom plate portion being connected to the lower edges of the first rear rim portion and the opposed first lateral portions; and closure element covering means attached to and completely covering the outer surfaces of said cover element and attached to the first rear rim portion, said closure element covering means extending under and being attached to the rear portion of the bottom plate; the said second front wall being spaced inwardly from the first front wall a distance sufficient for the upper edge of the second front wall to pass the lower edge of the first front wall as the box is opened or closed.

3. A display box comprising: a closure element having a top wall and a first rim depending from said top wall, said first rim including a first front wall with a lower edge, opposed first lateral portions, and a first rear rim portion; a bottom element having a bottom wall and a second rim upstanding from said bottom wall, said second rim including a second front wall with an upper edge, opposed second lateral portions, and a second rear portion; said second rim being of greater height than one-half the height of the said first rim; a bottom plate of substantially the same general configuration as said bottom wall, said bottom plate having a transverse bend dividing the bottom plate into a forward bottom plate portion and a rear bottom plate portion; said forward bottom plate portion being secured to the undersurface of said bottom wall; said rear bottom plate portion being connected to the lower edges of the first rear rim portion and the opposed first lateral portions; and closure element covering means attached to and completely covering the outer surfaces of said cover element and attached to the first rear rim portion, said closure element covering means extending under and being attached to the rear portion of the bottom plate; the said second front wall being spaced inwardly from the first front wall a distance sufficient for the upper edge of the second front wall to pass the lower edge of the first front wall as the box is opened or closed.

4. A display box comprising: a closure element having a top wall and a first rim depending from said top wall, said first rim including a first front wall with a lower edge, opposed first lateral portions, and a first rear rim portion; a bottom element having a bottom wall and a second rim upstanding from said bottom wall, said second rim including a second front wall with an upper edge, opposed second lateral portions and a second rear rim portion; and means pivotally connecting the bottom element to said opposed first lateral portions for rotation about an axis passing through the rear halves of said opposed first lateral portions; said upper edge of the second front wall being spaced from the inner surface of the first front wall in the closed position of said box a distance sufficient for the upper edge of the second front wall to pass the lower edge of the first front wall as the box is opened or closed.

SIMON QUARTIN.
